UNITED STATES PATENT OFFICE.

FRANK B. FREEMAN, OF DAYTON, KENTUCKY, ASSIGNOR TO THE KROHN FECHHEIMER COMPANY, OF CINCINNATI, OHIO, A CORPORATION OF OHIO.

SHOE-EDGING MACHINE.

1,209,277.

Specification of Letters Patent. Patented Dec. 19, 1916.

Application filed November 29, 1915. Serial No. 63,917.

To all whom it may concern:
Be it known that I, FRANK B. FREEMAN, a citizen of the United States, and a resident of Dayton, in the county of Campbell and State of Kentucky, have invented certain new and useful Improvements in Shoe-Edging Machines, of which the following is a full, clear, and exact description, reference being had to the accompanying drawings, forming part of this specification.

My invention relates to shoe edging machines in which an edging tool is caused to vibrate rapidly and is adapted to be applied in the presence of a mild heat to the edge 15 of a shoe sole after the same has been blackened.

As is well known in the art, the gums and stains employed to blacken the edge of the sole of a shoe after it has been properly 20 trimmed require to be burnished into the leather by means of rubbing them with a proper edging tool in the presence of heat, thereby causing the gums and stains to be absorbed into the leather owing to the melting 25 and rubbing thereof. There have been many devices in the art for this purpose, some of which are cumbersome and difficult to operate and others very expensive in construction.

It is the object of my invention to provide 30 a device for causing vibration of an edging tool which is simple to operate, durable and inexpensive, and in which a square vibratory motion is given to the edging tool as distinguished from a pendulum or a crank-motion, that is now generally the case in the 35 art, thereby providing a smoother and more rapid working tool for the work. These objects I accomplish by that certain construction and arrangement of parts to be 40 hereinafter more specifically pointed out and claimed.

In the drawings, Figure 1 is a side elevation of the device, partly broken away so 45 as to show a portion of the vibrating bar in section. Fig. 2 is a top plan view of the base plate of the device. Fig. 3 is a detail elevation of the tool holder and tools, broken away at the center. Fig. 4 is a front elevational detail of the device.

Mounted on a hollow standard 1, which serves as a conduit for the gas, if desired, is the base plate 2 of the vibrator device. A small gas pipe 3 is inserted into the stand- 50 ard and serves to provide a small flame 4

for the requisite heating during the edging operation.

The base plate 2 has a T-slot 5 in its upper surface, and in this slot lies the T-shaped vibrating bar having the arm portion 6 and the head portion 7. The relative sizes of slot and bar are such that the bar may slide laterally in the slot, but will be held against moving in and out by interengagement of the head or T-portions of the bar and slot. 65

Mounted over the base plate 2 is the top plate 8 of the device, which has a vertical journal or boss 9 for revolubly mounting the vertical shaft 10. At the top of the shaft 10 is fixed the horizontal driving pulley 11, 70 which is adapted to be operated by a belt or cord 12, the belt being brought around two vertical pulleys 13. These pulleys are journaled on each side of an arm 14, mounted on the vertical journal or boss 9 and serve to 75 turn at right angles the belt 12 driven from overhead, as is ordinarily the case in a factory.

The vertical shaft 10 has an eccentric stud 15 on its lower end. The T-bar has a slot 16 80 in its upper surface and a sliding block 17 pierced with a hole 18 is seated in this slot. The eccentric stud 15 is adapted to engage the hole 18 in the sliding block.

It can be seen that when the shaft 10 is 85 rotated, the T-bar will be vibrated laterally with a perfectly square motion, all the balance of the motion of the eccentric stud being taken up by the sliding block 17 moving in its slot in the bar and the bar being held 90 against any but lateral motion by its engagement in the T portion of the slot.

Mounted in the outer end of the portion 6 of the T-bar, is a pin 19, having a cap 20 on the end, preferably screwed into it. On this 95 pin is slidably mounted a tool holder 21, having flanges 22 to fit over them and a spring 23 to hold it in place engaging the bar by its flanges. The spring 23 may be provided with a chamber 23^a (Fig. 3) in the 100 tool holder. On this tool holder are located the two extending posts 24, each having a key 25 on it and a spring 26 coiled around it. The tubular ends 27 of the edging tools 28 fit over the posts and have slots 105 to engage the keys. The ends 27 of the tools are notched to engage spring fingers 29 on the holder, thereby holding them in place.

It can be seen that the tools may be pushed over the posts on the holder and will then 110

snap into place. The holder can be pulled out against the spring pressure at 23, freeing its flanges 22 from the bar, so that it may be reversed to present either of the two tools that is desired to the work, without stopping the bar from vibrating.

A slot is provided in the top portion 8 of the casing of the device, and a pin 30 mounted on the boss 9 over the top of the slot 10 serves as a mounting for a roller 31. This roller is of a size to extend down to just short of a contact with the bar member 6.

In operating the machine, the edging tools to be used on the work at hand are snapped down onto the holder. The operator then 15 presses the shoe sole to be worked on against the lower edging tool. This pressing up moves up slightly the bar portion 6, thereby causing the roller 31 to serve as a roller 20 bearing for the upper side of the bar portion 6. The shoe is then moved around manually by the operator, so as to accomplish the edging operation referred to above. Tools may be changed for varying pieces of 25 work, and the tool holder may be reversed as above described.

It is readily seen that the vibrator now shown and described is of simple structure and effective operation, fulfilling all the 30 necessary functions of an edging tool vibrator in a safe and efficient manner.

It is to be noted also that the design of the machine is such as to completely safeguard an operative, all moving parts being 35 inclosed.

Having thus described my invention, what I claim as new and desire to secure by Letters Patent, is:—

1. In a device of the character described, a base plate, means for mounting the same, 40 a slot in the base plate, a bar in the slot extending beyond the base plate, said bar and slot each having a T-portion, a top plate, means therein for journaling a vertical shaft, a sliding member in the bar, and an 45 eccentric stud on the shaft to engage said sliding member, to cause the bar to slide in the slot, for the purpose described.

2. In a device of the character described, in combination with a casing, and a member 50 slidably mounted therein so as to slide laterally only, a depending tool secured to said member and against which the work is to be pressed, a roller bearing, and means for mounting the same in the casing so as to 55 contact with the upper side of the sliding member.

3. In a device of the character described, in combination with a casing, and a member 60 slidably mounted therein so as to slide laterally only, a depending tool secured to said member and against which the work is to be pressed, a roller bearing, and means for mounting the same in the casing so as to 65 contact with the upper side of the sliding member when the said member is strained upwardly by the upward pressure of the work.

FRANK B. FREEMAN.
